HANDBAG

Walton B. Crane, Beverly Hills, Calif., assignor to
Allied Plastics Company, Los Angeles, Calif.,
a partnership composed of Dwight C. Hirsh and
Harry G. Long

Application August 6, 1945, Serial No. 609,258

9 Claims. (Cl. 132—79)

1

My invention relates generally to handbags of a class incorporating many of the features of a vanity case, and designed especially to be made up of injection molded plastic materials, though not necessarily limited thereto.

A general object of the invention is the provision of a handbag or large vanity case adapted to be formed of rigid plastic materials and incorporating unique and attractive features of design, convenience and utility.

To attain the above object I have created a novel style of handbag having a flat box-like body which may be held open upon the palm of the hand like a powder compact, and with a hinged cover bearing a mirror on its inner side which may be tilted back for the bearer's self-inspection. For added convenience and utility, and as a unique feature of especial attractiveness, I have placed the handle on the same end of the body with the hinges and have so constructed the handle and the hinges that the handle makes both a brace for the open cover and a retaining band around the bearer's finger, so that the handbag may be conveniently held open and with one hand. This location of the handle brings the opening edge of the cover to the lower end of the bag when the bag is closed and carried by the handle. The end straps of the handle have been utilized not only to attach the handle but to form a seal between the cover and the body. Except for the metal fastenings and the mirror, the entire device may be made of injection molded plastic material.

The exact manner in which the foregoing and other objects of the invention have been attained will more readily be understood by consideration of the following detailed description and the accompanying drawings, in which:

Figure 1 is a perspective view of my invention in closed position;

Figure 2 is a perspective view with the handbag in open position as it would be held on the palm of the hand or placed on a table;

Figure 3 is an enlarged fragmentary sectional view of a portion of the body of the handbag, illustrating a preferred method of clasping the cover;

Figure 4 is a transverse sectional view on an intermediate scale taken on the line 4—4 of Fig. 1;

Figure 5 is a transverse sectional view on the same scale as Fig. 4 and at right angles thereto, taken on the line 5—5 of Fig. 1; and

Figure 6 is a fragmentary sectional view on the same scale showing the cover in open position and illustrating the construction of the hinges.

2

Throughout this description and in the appended claims, terms of comparative location such as upper and lower, above and below, refer to locations in the open position as viewed in Fig. 2.

Considering now the drawings in detail, 10 indicates the body portion of the handbag, preferably of rigid plastic material, and having low side walls with rounded corners. One wall of the body 10 is partially cut away to form a recess indicated at 11 in Figs. 2, 5, and 6, and the lateral margins of this recess have reinforcing flanges 12, which serve also as hinge supports, on the outer side of the wall. The marginal portion 13 of the wall below the recess 11 and between the flanges 12 is offset outwardly in alignment with the outer edges of the flanges. Hinge pins 14, set in the flanges 12, pivotally support a cover 15, engaging a marginal flange 16 thereof which fits within the recess 11 and is offset outwardly to lie in alignment with the flanges 12 and the marginal portion 13 of the wall when the cover is closed. The cover 15 is preferably of rigid plastic material and rests, when closed, upon the side walls of the body 10 so as to join therewith in a smooth exterior alignment. A mirror 17, affixed to the inner side of the cover 15 by tabs 18, extends substantially to the inner side of all the side walls of the body 10, and not only affords a large area of reflection but gives support and reinforcement to the cover. To hold the cover in closed position, a flange 19, which is offset outwardly to lie outside the coacting wall of the body 10, is provided with a socket 20 to receive the ball of a ball and spring latch 21 set in the coacting wall. Preferably this latch 21 is in the wall of the body 35 opposite the hinge pins 14, but it may be placed elsewhere, as in either of the adjacent walls, and also be of some other form of latching device.

A handle 22 extends outwardly from the end 40 of the body 10 upon which the cover 15 is pivoted. The handle 22 is preferably a strap of rigid plastic material having a central portion 23, to be grasped by the bearer, and end portions 24 fastened to the walls of the body 10 by rivets 25. The end portions 24 are coextensive in width with 45 the combined thickness of the body 10 and the cover 15, so as to cover completely the walls of the body and the edge of the cover and to conceal and form an outer seal to their juncture, and they extend around the lower corners of the body 10 to the flange 19, and join the central portion 23 in similar curves, giving a symmetrical appearance to the whole handbag.

When in the utilization of the device, the cover 55 15 is closed, its junction with the body 10 is effec-

tively sealed by the end straps 24, the flange 19, and the aligned flange 16 and offset wall portion 13. When the cover 15 is open, the converging curved corners of the end straps 24 engage the edges of the cover and hold it in outwardly tilted position. The support afforded by the end straps 24 takes the strain from the hinge pins 14 and makes their fracture or the fracture of their mountings less likely. The outwardly offset mounting of the hinge pins 14 cooperates with the flange 16 to project the opened cover outwardly toward the handle 22, so that it more quickly engages the end straps 24 and is held at only a moderate inclination. This moderate inclination permits finger space between the cover 15 and the central portion 23 of the handle. The handbag may then be held on the palm of one hand with the bearer's fingers between the cover and the handle in a manner giving effective support and requiring no finger pressure of gripping. Only when the handbag is thus placed horizontally is the flange 19 readily available for unfastening the latch 21, or even visible. While I prefer to have all parts of the handbag of homogeneous and rigid material it will be seen that other materials may be substituted in part. The central portion 23 of the handle 22, as shown in dotted lines in Fig. 2, might for example be made of pliable material suspended between the curved corners of rigid end straps 24, without affecting the manner in which the end straps hold the cover 15 or afford finger space. Parts of the body 10 might also obviously be of pliable material. Various changes in detail may be made without departing from the spirit and scope of the appended claims which best define the invention.

I claim:

1. A handbag having a flat box-like rigid body open on one side of greatest dimension and having one end wall partially cut away to form a recess therein and marginal flanges laterally of said recess on the outer side of said wall, a rigid cover proportioned to rest upon the upper margin of the walls of said body and having a downwardly extending marginal flange adapted to fit within said recess, pivotal supports for said cover connecting the said marginal flange thereof with said lateral marginal flanges of said recess, and a rigid handle on the same end of said body as said pivotal supports, said handle having a center portion and end straps rigidly affixing said handle to said body, said end straps extending around the corners of said body on the end opposite said pivotal supports and extending upwardly above the upper margin of said body to conceal the juncture of said body and said cover, said end straps being curved inwardly to the said center portion and adapted by their converging curvature to engage the corners of said cover when said cover is open and to then hold said cover at an outward inclination and spaced from said center portion sufficiently to permit the insertion of fingers therebetween.

2. A handbag having a flat box-like rigid body open on one side of greatest dimension, a rigid cover for said open side proportioned to rest upon the upper margins of the walls of said body, pivotal supports connecting said cover with one end of said body, and a rigid handle on the same end of said body as said pivotal supports, said handle having a center portion and end straps rigidly affixing said handle to said body, said end straps extending upwardly above the upper margin of said body to conceal the juncture of said body and said cover and being curved inwardly to the said

center portion and adapted by their converging curvature to engage the corners of said cover when said cover is open and to then hold said cover at an outward inclination and spaced from said center portion sufficiently to permit the insertion of fingers therebetween.

3. A handbag having a flat box-like rigid body open on one side of greatest dimension, a rigid cover for said open side, a mirror carried by said cover on the inner side thereof, pivotal supports connecting said cover with one end of said body, and a rigid handle on the same end of said body as said pivotal supports, said handle having a center portion and end straps rigidly affixing said handle to said body, said end straps being curved upwardly to the said center portion and adapted by their converging curvature to engage the corners of said cover when said cover is open and to then hold said cover at an outward inclination and spaced from said center portion sufficiently to permit the insertion of fingers therebetween.

4. A handbag having a flat box-like rigid body open on one side of greatest dimension, a rigid cover for said open side, pivotal supports connecting said cover with one end of said body, and a rigid handle on the same end of said body as said pivotal supports, said handle having a center portion and end straps rigidly affixing said handle to said body, said end straps extending upwardly above the upper margin of said body to conceal the juncture of said body and said cover and being curved inwardly to the said center portion and adapted by their converging curvature to engage the corners of said cover at an outward inclination.

5. A handbag having a flat box-like rigid body open on one side of greatest dimension and having one end wall partially cut away to form a recess therein and marginal flanges laterally of said recess on the outer side of said wall, a rigid cover proportioned to rest upon the upper margin of the walls of said body and having a downwardly extending marginal flange adapted to fit within said recess, pivotal supports for said cover connecting the said marginal flange thereof with said lateral marginal flanges of said recess, and a rigid handle on the same end of said body as said pivotal supports, said handle having a center portion and end straps rigidly affixing said handle to said body, said end straps extending around the corners of said body on the end opposite said pivotal supports and extending upwardly above the upper margin of said body to conceal the juncture of said body and said cover, said end straps being curved inwardly to the said center portion and adapted by their converging curvature to engage the corners of said cover when said cover is open and to then hold said cover spaced from said center portion sufficiently to permit the insertion of fingers therebetween.

6. A handbag having a flat box-like rigid body open on one side of greatest dimension, a rigid cover for said open side, a handle having end straps rigidly affixed to said body, said end straps being convergently curved toward the center portion of said handle, and hinges supporting said cover on the end of said body adjacent said handle, said hinges being offset from said cover and from said body so as to cause the adjacent corners of said cover to engage the curved portions of said end straps when said cover is open and to then hold said cover at an outward inclination and spaced from said handle sufficiently to permit the insertion of fingers therebetween.

7. A handbag having a flat box-like rigid body

open on one side of greatest dimensions, a rigid cover for said open side, a handle having end straps rigidly affixed to said body, said end straps being convergently curved toward the center portion of said handle, and hinges supporting said cover on the end of said body adjacent said handle, said hinges being offset from said cover so as to cause the adjacent corners of said cover to engage the curved portions of said end straps when said cover is open and to then hold said cover spaced from said handle sufficiently to permit the insertion of fingers therebetween.

8. A handbag having a box-like body open on its upper side, a rigid handle carried by said body and having a central portion spaced from one end of said body and end straps engaging the sides of said body adjacent said end, a rigid cover proportioned to fit between said end straps, said end straps extending upwardly above the upper margin of said body and concealing the juncture of said cover and said body, and hinges connecting said cover to said body at the end thereof adjacent said handle, said hinges being offset from said cover so as to cause the adjacent cor-

ners of said cover to engage said handle when said cover is open and to then hold said cover at an outward inclination.

9. A handbag having a box-like body open on its upper side, a rigid handle carried by said body and having a central portion spaced from one end of said body and end straps engaging the sides of said body adjacent said end, a rigid cover, and hinges connecting said cover to said body at the end thereof adjacent said handle, said hinges being offset from said cover so as to cause the adjacent corners of said cover to engage said handle when said cover is open and to then hold said cover at an outward inclination.
